UNITED STATES PATENT OFFICE

FREDERICK J. ERNST, OF YAKIMA, WASHINGTON

DESIGN FOR AN INTERIOR AUTO RACK

Application filed January 15, 1930. Serial No. 34,140. Term of patent 14 years.

To all whom it may concern:

Be it known that I, FREDERICK J. ERNST, a citizen of the United States, residing at Yakima, in the county of Yakima and State of Washington, have invented a new, original, and ornamental Design for Interior Auto Racks, of which the following is a specification, reference being had to the accompanying drawing, forming a part thereof.

In the drawings:

The figure is a perspective view of an interior auto rack showing my new design.

I claim:

The ornamental design for an interior auto rack, as shown.

In witness whereof, I hereunto subscribe my name this 7th day of January, A. D. 1930.

FREDERICK J. ERNST.
